(57) **CLAIM**

The ornamental design for a vehicle driver side air bag cover as shown and described.

DESCRIPTION

FIG. 1 is a front elevational view of a vehicle driver side air bag cover showing our new design;

FIG. 2 is a left side elevational view thereof;

FIG. 3 is a right side elevational view thereof;

FIG. 4 is a top plan view thereof;

FIG. 5 is a bottom plan view thereof.

FIG. 6 is a top, front and right side perspective view thereof; and,

FIG. 7 is a top, front and left side perspective view thereof.

The ghosted or low contrasted showing of the vehicle driver side air bag cover is provided for the purposes of illustrating portions that form no part of the claimed design.

1 Claim, 7 Drawing Sheets
